UNITED STATES PATENT OFFICE.

STEPHEN ZSIKAY, OF PHILADELPHIA, PENNSYLVANIA.

FOLDABLE STOOL.

Application filed September 22, 1921. Serial No. 502,383.

To all whom it may concern:

Be it known that I, STEPHEN ZSIKAY, a citizen of Hungary, residing at Philadelphia, in the county of Philadelphia and

5 State of Pennsylvania, have invented certain new and useful Improvements in Foldable Stools, of which the following is a specification.

The primary object of the invention is 10 the provision of a stool adapted as a foldable sporting chair readily positioned for use when desired and easily disassembled for convenient folding and packing for transportation.

15 A further object of the invention is the provision of a foldable camp stool wherein the flexible seat and separate leg members are readily disassembled for compact assembly when desiring to carry the stool from 20 one place to another, the same being readily set up for use whenever desired.

A still further object of the invention is the provision of a foldable stool that is easy and inexpensive to manufacture although 25 possessing great strength and durability.

With these general objects in view and others that will appear as the nature of the invention is better understood, the same consists in the novel form, combination and 30 arrangement of parts hereinafter more fully described and shown in the accompanying drawing, in which like designating characters refer to corresponding parts throughout the several views.

35 In the drawing,

Figure 1 is a side elevation of the invention set up for use,

Figure 2 is an end elevation thereof,

40 Figure 3 is an enlarged detail sectional view through a corner portion of the device,

Figure 4 is a similar sectional view taken upon line IV-IV of Figure 3,

Figure 5 is a plan view of a portion of 45 the flexible seat removed and broken away and

Figure 6 is a longitudinal sectional view of one of the spring thimbles employed with the retaining sockets of the leg members.

50 It being understood that my invention is of the general type commonly designated as camp stools; the invention broadly includes oppositely positionable identical leg members or supports 10 and 11 with a flexible seat 12 detachably connected between the upper ends of the leg members, whereby a

substantially horizontal seat is provided when the leg members are outstretched in parallel relations. The leg member 10 includes two rails 13 substantially centrally 60 pivoted together by a bolt 14 for assuming either a folded or an X-shaped formation as desired. The opposite leg member 11 consists of identical rails 13' pivoted together at 14' whereby the leg members 10 and 11 65 may each assume X-shaped arrangement and be oppositely positioned for mounting the seat 12 upon the upper ends of the rails 13.

Suitable spacing means for the leg members 10 and 11 consists of hooks 15 pivoted 70 as at 16 to corresponding rails of the leg members and having down-turned ends 17 of the hooks adapted for reception in spaced loops 18 carried by the other rails of said leg members 10 and 11. When said leg 75 members are set up for use with the hooks 15 securing them in parallel relations as shown in Figures 1 and 2, a strong support is provided for the seat 12 detachably mounted upon the leg members in the manner hereinafter described.

Each rail 13 and 13' is provided with an axial socket 19 in its upper end with a spring thimble 20 secured in the socket having a contracted slotted inner end 21 spaced 85 from the inner end or bottom 22 of the socket. A cleat 23 is permanently secured to each end of the seat 12, the seat being flexible and formed of such material as canvas easily secured around the end cleats 90 23. Posts or spindles 24 perpendicularly project from the lower faces of the cleats 23 adjacent the opposite ends of the cleats and are adapted for slidably positioning in the socket thimbles 20. A head 25 is provided upon the free end of each post 24 for positioning inwardly of and beneath the resilient holding portion 21 of the thimble 20, with an intermediate contracted portion 26 of the spindle 24 engaged by said 100 thimble portion 21.

The spindles 24 upon each cleat 23 are properly spaced apart for ready insertion within the socket thimbles 20 when the leg members 10 and 11 are positioned for use 105 while the resilient portions 21 of the thimbles retain the spindles 24 in the sockets 19 with the flexible seat 12 in stretched arrangement between the cleats 23 at the upper ends of the rails 13 and 13' of the leg 110 members 10 and 11.

When desired to transport the stool, the

spindles 24 are readily pulled out of the socket thimbles 20 and upon disconnecting the hooks 15, the leg members 10 and 11 are folded together upon the pivots 14 and 14' respectively, permitting the leg members to be placed upon the flexible seat 12 for wrapping around the leg members and in which position, the straps 27 at one end of the seat 12 may be engaged by the buckles 28 at the opposite end thereof and providing a convenient manner of carrying the device. A suitable hand hold or loop 29 is also preferably provided upon the seat 12 for grasping in carrying the folded camp stool wherever desired.

From this description of the invention, the complete operation thereof will be fully understood including the folding of the device for transportation and the manner of setting the same up for use as a stool or chair. While the form of the invention set forth is believed preferable, it will be understood that minor changes may be made therein without departing from the spirit and scope of the invention.

What is claimed as new is:

A camp stool comprising a pair of leg members each including a pair of substantially centrally pivotally connected rails, rigid spacing connections adapted to detachably connect the lower ends of the leg

members when set up for use in parallel arrangement, the rigid spacing connections each comprising a hook-shaped member pivotally secured adjacent the lower end of one of said rails forming a part of one of said legs and adapted to engage spaced loops carried by one of said rails forming a part of the oppositely disposed leg, the upper ends of said rails having axially arranged sockets, spring thimbles positioned in said sockets and having slotted and contracted inner ends providing arcuate gripping jaws, a flexible seat member, a transverse cleat carried at each end of the seat member, posts fixed to and perpendicularly projecting from the opposite ends of the cleats, said posts having heads at their free ends and adapted for removable positioning within said thimbles when the device is set up for use with the heads retainingly engaged by said jaws, straps carried adjacent one end of said flexible seat, buckles carried adjacent the opposite end of said seat and adapted for engaging the said straps for holding the device in folded arrangement, and a loop carried by the said flexible seat for providing a handle for the folded camp stool.

In testimony whereof I affix my signature.

STEPHEN ZSIKAY.
